UNITED STATES PATENT OFFICE.

CHRISTOPHER W. LEVALLEY, OF MILWAUKEE, WISCONSIN.

DESIGN FOR A CHAIN-LINK.

SPECIFICATION forming part of Design No. 32,563, dated April 24, 1900.

Application filed March 21, 1900. Serial No. 9,620. Term of patent 14 years.

To all whom it may concern:

Be it known that I, CHRISTOPHER W. LEVALLEY, a citizen of the United States, residing at Milwaukee, in the county of Milwaukee and State of Wisconsin, have invented and produced a new and original Design for Chain-Links, of which the following is a specification.

Figure 1 is a plan view of a single drive-chain link made according to my new and original design. Fig. 2 is an edge view of the same.

The chain-link consists of the side bars *a a*, the cross or end bar *b*, provided with a hook *c*, and the opposite cross or end bar *d*. Upon the upper side of each side bar there is formed in bas-relief an arrow-shaped figure, with the point or head of the arrow pointing toward the hook. The nock or rear end of the arrow terminates a short distance from the cross or end bar *d*, so that the side bar is vacant be-

tween the nock or rear end of the arrow and the end bar *d*, the thickness of the side bar at this vacant space being thereby reduced as compared with the thickness of the end bar throughout the portion occupied by the arrow, this being represented best in Fig. 2.

The essential and characteristic feature of my design is the link having the side bars formed with arrow-shaped designs in bas-relief, the rear or nock ends of the arrows being toward the plane cross-bar *d*.

Having described my invention, what I claim as new, and desire to secure by Letters Patent, is—

The design for a chain-link substantially as herein shown and described.

CHRISTOPHER W. LEVALLEY.
